GOLF CLUB HEAD

James A. Karns, Akron, Ohio, assignor to National Die Casting Company, Chicago, Ill., a corporation of Illinois

Application June 6, 1956, Serial No. 41,779

Term of patent 14 years

(Cl. D34—5)

Fig. 1 is a top view of a golf club head embodying my new design;

Fig. 2 is a front elevational view of the golf club head of Fig. 1;

Fig. 3 is a bottom view of the golf club head of Fig. 1; and

Fig. 4 is an elevational view of the toe end of the club.

The dominant feature of my design for a golf club head resides in the contrastingly colored insert of the configuration disclosed on the striking face as disclosed in Fig. 2 and which insert is visible from the top as particularly shown in Fig. 1.

I claim:

The ornamental design for a golf club head, substantially as shown and described.
